UNITED STATES PATENT OFFICE.

WILLIAM H. KYNELL, OF BATTLE CREEK, MICHIGAN.

FLY-SHUTTLE ATTACHMENT FOR CARPET-LOOMS.

SPECIFICATION forming part of Letters Patent No. 537,045, dated April 9, 1895.

Application filed November 9, 1894. Serial No. 528,344. (No model.)

To all whom it may concern:

Be it known that I, WILLIAM H. KYNELL, a citizen of the United States, residing at Battle Creek, in the county of Calhoun, State of Michigan, have invented a new and useful Fly-Shuttle Attachment for Carpet-Looms, of which the following is a specification.

This invention relates to that class of looms employing fly-shuttles which are thrown back and forth through the warp across the batten by picker-sticks at the ends of said batten.

The object of this invention is to give to the shuttle a quick, forcible and never failing momentum to carry it across the batten of the loom as nearly as possible in effect as though thrown by hand, by means of a pivoted lever, the free end of said lever being attached by flexible means to the picker-sticks which strike against the ends of the shuttle to throw the same, said lever being operated by means attached to the batten and to the loom-frame to swing its free end in either lateral direction when the batten is swung forward and backward, all as more particularly described and claimed below.

In the drawings forming a part of this specification, Figure 1, is a perspective view of a loom with my improvements attached; Fig. 2, enlarged broken details from Fig. 1, in perspective; Fig. 3, a plan of a detail from Figs. 1, 2, and 4; Fig. 4, an enlarged plan of details from Fig. 2, illustrating the operation, and Fig. 5, an enlarged perspective of details from Fig. 2, separated showing their construction.

Referring to the lettered parts and numerals of the drawings, A is a loom, and B the swinging batten carrying the reed C, for closing the weft as in ordinary constructions.

On each end of the batten B, is a binder D, to receive the shuttle E, as it is thrown back and forth across the batten. One of the walls of each binder D, yields outward against the resistance of the spring 2, Fig. 1. This wall is removed in Fig. 2, to show the shuttle E, and the upper end of the picker-stick F, against the end of the shuttle ready to throw it across the batten B, into the binder at the other end of the batten. Fig. 1, shows the shuttle E, in the clamp D, at said other end. The office of these binders is of course to re-

tain the shuttle E, in place until forced out by the picker-sticks F. These picker-sticks F, are pivoted at the lower end at H, to the side standards I, of the frame of the batten 55 B, so as to swing laterally during the operation of throwing the shuttle E. The upper ends of the picker-sticks F, work in a slot J, in the ends of the batten B.

On the under side of the batten B, at the center is pivoted one end of a lever L, the other end of said lever projecting forward, and to which cords N, or their equivalents are attached. See Figs. 1, 2, and 5. These cords N, extend each way laterally, pass 65 through slots O, in the picker-sticks F, and are attached at P, to the free ends of spring-bars R, which bars are attached at the lower end to the picker-sticks F, Fig. 2. At S, is shown a wedge shaped adjustable block by 70 the raising or lowering of which the tension of the spring-bars R is varied.

The pivoted end of the lever L, is enlarged and thickened up at the rear forming a raised cam portion T, from the apex of which, said 75 cam portion slopes downwardly, forwardly and each way laterally. This pivoted end of the lever L, is provided with upwardly extending projections U, one on each side, Figs. 2 and 5, for a purpose explained in the operation.

The lever L, is operated by a hooked bar W, Figs. 2, 3, and 4, said bar being provided with a spade like end X, and having a hook Z, on each side at the junction of said spade 85 like end and the bar. The end of this bar W, opposite to the spade like end is pivoted at e, to the front beam c, of the loom-frame A, Figs. 1 and 2, to allow the hooked end to play laterally during the operation. This end of the bar W, rests loosely on the apex of the raised cam portion of the lever L, between the projections U, Figs. 2 and 4.

To add to the strength of the pivotal support of the lever L, and for convenience of 95 construction, I connect the projections U, by a bar f, and pivot this bar, at m to a plate i, on the under side of the batten B, Figs. 2 and 5. I also provide a support n, to which the end V, of the lever L, is pivoted at r. 100 This support n, is provided with projections t, which pass up through holes in the ends of

the plate *i*, and are attached to the batten *B*, and thus these parts are held together and attached to the batten.

- In the operation, referring to Figs. 1 and 2, the batten *B*, has just been swung rearwardly away from the operator after closing a thread of weft during its forward movement, which of course will be readily understood by weavers. During the rearward swing of the batten, the left hand hook *Z*, of the hooked bar *W*, caught onto the left hand projection *U*, of the lever *L*, and swung the free end of said lever to the right. This action pulled with a sudden movement on the left hand picker-stick *R*, by means of its connecting cord *N*, forcing said picker-stick against the end of the shuttle *E*, and causing it to fly across the batten to the other end. In Fig. 1, the shuttle *E*, is supposed to be just starting, and in Fig. 2, it has crossed over into the clamp *D*, at the right hand end. The shock caused by the sudden swing of the lever *L*, is first received on the spring-bar *R*, and thus cushioned before exerting the force on the picker-stick *F*, the cushioned force serving to bring the picker-stick firmly against the end of the shuttle *E*, before said shuttle is thrown by the further movement of the picker-stick. Continuing the operation, the batten is now swung forward to close the thread of weft just carried through the warp by the shuttle, and so on, the shuttle being thrown across the batten back and forth at each rearward swing.
- No warp and weft are here shown, but the supply of the weft from the shuttle and closing it in the warp by the forward swing of the batten will be readily understood by those skilled in the art.
- Referring to Fig. 4, to further explain the operation, the lever *L*, and the hooked bar *W*, are in the position they occupy when having just operated on the right hand picker-stick. Now when the batten is swung forward toward the operator the spade like end *V*, of the bar *W*, will slide over the apex of the raised cam portion *T*, to the other side as shown by dotted position in said Fig. 4, and its left hand hook *Z*, will catch the left hand projection *U*, when the batten is again swung to the rearward. The dotted position shows the hook just caught as when the batten has started to swing back. This makes a positive, never failing movement, and gives that peculiar and proper momentum to the shuttle *E*, necessary to carry it across the batten, as explained.

Having thus described my invention, what I claim as new, and desire to secure by Letters Patent of the United States, is—

1. In a fly shuttle attachment, the combina-

tion, of a batten, a picker-stick at each end of said batten, a lever provided with the raised cam portion and pivoted centrally to said batten, and provided with upward projections at the sides, means connecting the free end of said lever to the picker-sticks, and a bar having a hook at each side of one end, said end being adapted to slide over the apex of said cam portion of the lever, the other end of said bar being pivoted to a fixed support, substantially as set forth.

2. In a fly shuttle attachment, the combination, of a batten, a picker-stick at each end of said batten, a lever provided with the raised cam portion and pivoted centrally to said batten, and provided with upward projections at the sides, means connecting the free end of said lever to the picker-sticks, and a bar having a spade like end with hooks at the junction of said end and bar, the other end of said bar being pivoted to a fixed support, substantially as set forth.

3. In a fly shuttle attachment, the combination, of a batten, a picker stick at each end of said batten, a lever provided with the raised cam portion and pivoted centrally to said batten, and provided with upward projections at the sides, cushioning springs attached to the picker sticks, cords attached to the free end of said lever, passing through the picker-sticks and attached to the springs, and a bar having a hook at each side of one end, said end being adapted to slide over the apex of said cam portion of the lever, the other end of said bar being pivoted to a fixed support, substantially as set forth.

4. In a fly shuttle attachment, the combination, of a batten, a picker-stick at each end of said batten, a lever provided with the raised cam portion and upward projections at the sides, a bar connecting said projections, a plate attached centrally to the batten and to which the connecting bar of the projections is pivoted and a support beneath the one end of the lever, and centrally pivoted to said end, said support being attached to the batten, means connecting the free end of said lever to the picker-sticks, and a bar having a hook at each side of one end, said end being adapted to slide over the apex of said cam portion of the lever, the other end of said bar being pivoted to a fixed support, substantially as set forth.

In testimony of the foregoing I have hereunto subscribed my name in the presence of two witnesses.

WILLIAM H. KYNELL.
